DIRECT RECIPROCATORY DRIVE FOR
MOTOR-DRIVEN COMPRESSORS AND
THE LIKEChristopher A. Armstrong, Richmond,
British Columbia, Canada

Application February 12, 1953, Serial No. 336,620

2 Claims. (Cl. 230—58)

1

My invention relates to improvements in direct reciprocating drive for motor driven compressors and the like.

The objects of the present invention are to provide a motor having a stator and a rotor in which the rotor forms a reciprocating element adapted for connection to a reciprocating part of the compressor or other power consuming machine to operate it; to provide that the rotor may impart one reciprocating cycle to each revolution, and to provide a mechanism where the part reciprocated by the rotor may serve as a cylinder for a compressor and the shaft on which the rotor part is journaled may serve in whole or in part as the piston for the compressor.

The single figure of the drawing is a vertical sectional view of a motor-compressor of a so-called sealed refrigerator unit.

The numeral 1 indicates a sealed vessel having a bottom wall 2, a side wall 3, a top closure 4 and a horizontal dividing wall 5 which divides the vessel into a suction chamber 7 and a compressed gas chamber 8. The suction chamber 7 is provided with an inlet opening 10 to which the suction pipe 11 from an expansion coil, not shown, is connected. The gas chamber 8 is provided with an outlet opening 12 to which a pipe 15 is adapted to be connected to return the compressed refrigerant to a liquid receiver, not shown.

Concentrically mounted within the vessel is a hollow vertical shaft 17 having an upper end closure 18, which closure forms the piston for a compressor generally indicated by the numeral 20, and is apertured as at 21 to form intake ports to said compressor. Slidably and rotatably mounted upon the shaft 17 is a sleeve 23 which forms the cylinder of the compressor 20 and is fitted with a top closure or cylinder head 24. The cylinder head 24 is provided with a recess 25 having in its base a valve port 26. The recess 25 is covered with a cap 28 having a discharge outlet 29 and housing the spring 30 of an outlet valve 31, which valve is adapted to close the valve port 26. A disk forming a suction valve 32 is mounted upon the piston or cylinder end closure 18 to cover the intake ports or apertures 21. The field windings or stator 34 of an electric motor 35 is mounted concentrically within the gas chamber 8 and its armature or rotor 36 is mounted upon the sleeve or cylinder 23 to rotate and reciprocate therewith within the magnetic field. The lower end of the sleeve 23 is fitted with a wobble plate 37 which is engaged on its upper and lower face adjacent its periphery by a pair of slippers 38 supported in a fixed position from a stationary part of the vessel structure.

The operation of the device is as follows:

2

When the motor circuit is closed the rotor will be caused to rotate and the sleeve or cylinder 23 will obviously rotate upon the hollow shaft 17. The wobble plate 37 is set at an angle of approximately ninety degrees from the axis of the sleeve upon which it is secured and as part of the plate which at the moment is engaged between the slippers is held against movement axially of the shaft, the sleeve or cylinder 23 together with the rotor 36 must move axially of the shaft 17, causing the cylinder head 24 to move toward and away from the piston 18, thus causing the compressor to function as such. The rotor 36 is preferably shorter in an axial direction than the stator 34, as shown, so that all the effective magnetic area of the rotor will be confined within the length of the field windings to the extent of the reciprocating movement of the stator, so that the torsional efficiency of the motor is unimpaired.

What I claim as my invention is:

1. A direct reciprocating drive for electric motors comprising a motor having a stator, a rotor and a stationary shaft, said rotor being mounted upon a sleeve, said sleeve being mounted for rotational and reciprocating movement upon the shaft, said sleeve having an end closure at one end and a wobble plate adjacent the opposite end of the rotor, and means supported on a stationary part adjacent the shaft for engaging the wobble plate adjacent its periphery whereby the rotor is reciprocated as it rotates within the stator, said shaft forming a piston and said sleeve forming a cylinder, said shaft having an inlet valve and said cylinder having an outlet valve.
2. Direct drive mechanism for operating a reciprocating compressor from the rotary drive of an electromotor, said drive mechanism comprising a fixed shaft, a sleeve rotatably and reciprocably mounted upon said shaft, said rotor being mounted upon said sleeve, said sleeve forming part of the cylinder of the compressor, and said shaft having an end closure and forming the piston for the compressor, said sleeve having secured thereupon a wobble plate, and means secured to a fixed part of the compressor providing slipping engagement with the wobble plate adjacent its periphery and reciprocating movement to the rotor and the compressor cylinder, said fixed shaft end closure having an inlet valve and said sleeve having an outlet valve.
